UNITED STATES PATENT OFFICE.

EUGEN STEIGER, OF ZURICH, SWITZERLAND.

ELECTRIC TIME-SWITCH.

1,292,122.

Specification of Letters Patent.

Patented Jan. 21, 1919.

Application filed April 22, 1916. Serial No. 92,960.

To all whom it may concern:

Be it known that I, EUGEN STEIGER, a citizen of the Swiss Confederation, and residing at Zurich, Switzerland, have invented 5 certain new and useful Improvements in Electric Time-Switches, of which the following is a specification.

The present invention has reference to improvements in time switches, such as are 10 used for automatically completing or breaking a light circuit, and it relates more particularly to a switch for this purpose which is operated automatically on the day light changing into twilight and vice versa, and the invention essentially resides in the construction, arrangement and coöperation of parts, as will hereinafter be fully described.

The time switches now extensively used for switching on and off the lights in the controlled circuit are almost exclusively of the clock type, operate mechanically always at a predetermined, set time, and must be reset for operating at any other time. In the case of staircase or street illumination with such automatic control the caretaker thus, to be on the safe side, is apt to set the time ahead of actual necessity, causing thereby undue waste of current and lamp material; and, furthermore, such time clocks do not cut the lamps in or out on a passing darkening, as would occur for instance during a thunderstorm; and as far as I am aware, time switches are not at all used in railroad service, where they could be employed to good advantage, especially on lines running through tunnels.

My improved twilight switch effectively does away with these and other drawbacks and operates promptly at any time the atmospheric light conditions render the lighting up or extinguishing of the controlled lamps necessary or advisable, and I will now describe its detailed construction and operation with reference to the accompanying drawing, in which are shown diagrammatical views of two modifications, Figure 1 representing a switch for stationary operation on alternating current, and Fig. 2 a switch for mobile continuous current operation.

Referring first to Fig. 1, WH denotes the 50 alternating current mains leading to a transformer Tr, which is tapped for instance for 4 and 30 volts. The 30 volt circuit is indicated by W^I, and the 4 volt circuit by W^{II}, W^{III} and W^{IV}. The circuit W^I includes the 55 coils a of a permanent horseshoe magnet a¹ and a selenium cell S^I, arranged in series.

In front of the poles of the magnet is arranged a sheet iron diaphragm b, as in a telephone, to which for the purpose of enhancing the oscillations a permanent horseshoe magnet c is fixed, the poles of the two magnets being oppositely disposed. From the magnet c extends a rod d, to the further end of which an insulator e is attached, 60 which carries two insulated conducting arms e¹, e². These latter are connected to the line W^{II} and oscillate with the insulator e between two pairs of contacts f¹, f², f³, f⁴. Contact f¹ is connected with contact f³, and 65 contact f² with contact f⁴. This arrangement A is on the one hand a secondary circuit relay, and on the other hand a current rectifier, inasmuch as by the crosswise grouping of the contact connections the alternating current is sent over the line G^{II} in 70 always the same direction through the solenoids g¹, g² of the polarized relay B. The double-armed oscillating beam h, which supports the solenoid armatures h¹, h², is provided with a two-contact arm h³ which is 75 normally pressed against the contact i¹ by the action of the draw-spring h⁴, which latter also withdraws the armatures from out of the solenoids, while they are drawn into 80 the latter by the solenoids and the arm h³ is laid over against contact i² when a sufficiently strong current excites the solenoids g¹, g². This two contact arrangement alternatively closes the circuits W^{III}, W^{IV} of a 85 switch relay C. The armature k of this relay is influenced by a spring t and by the electromagnet m, so that when no current is passing through the electromagnet the one end of the armature contacts with a contact 90 spring n and also with a contact terminal q¹ of a circuit FS, which includes a suitable switch D which serves to control the light- 95

ing system which is shown in the drawing as comprising lamps L. This circuit FS is also in continuous operative connection with the armature k at q². In the position 5 shown in the drawing the circuit W^{IV} is closed for operation except at the break at i². The armature k at the opposite end carries an insulated conducting lever k², to the free end of which is secured the insulating nose 10 k³. The armature l, is influenced by the electromagnet p and the spring o and carries at its upper end a catch l¹, adapted to lockingly coöperate with the insulated nose k³ of lever arm k². In the relative position of 15 the armatures k and l shown, the circuit W^{III} would be interrupted at k²—l¹.

In Fig. 2 GH indicates the direct current mains, of for instance 30 volts, by which coils 1 of a permanent horseshoe magnet 2 20 and a selenium cell S^{II} are served, as described with reference to Fig. 1. In front of the magnet poles vibrates a diaphragm 3 to which is fixed by means of the support 4 the contact beam 5, which, depending upon the 25 position of the diaphragm, contacts with one of the contacts 6 or 7, and which is itself connected up to the 4 volt line G. This contact beam alternately completes the circuits of a switch relay, such as described above.

30 The operation of the mechanisms shown in Fig. 1 is the following:—The diaphragm b is attracted by the magnet a¹ or is repulsed with the changing direction of current in the coils a. These oscillations are intensified by the magnet c, which is necessary as owing to the high resistance of selenium cell (up to 100,000 ohms) only very low currents (a few milliamperes) flow through the coils. Relatively higher currents cannot be used 40 without injury to the cell. If now the light striking the cell brightens up, the cell resistance diminishes and more current can pass through the coils; on dimming of the light the passage of current is correspondingly 45 reduced, and the diaphragm, in keeping therewith, will oscillate to a greater or lesser extent. In the former instance the contact between e¹, e² and f¹, f², f³, f⁴ will be of longer duration and more forcible than on 50 lesser oscillations of the membrane. A correspondingly varying amount of current will then flow through the circuits W^{II} and G^{II}, which in turn excites the solenoids g¹, g² (relay B) more or less strongly, with the 55 result that their armatures h¹, h² are drawn more or less deeply into the solenoids, the contact beam h³ then contacting either at i² or at i¹, for respectively closing the circuits W^{IV} or W^{III}. Thus the circuit W^{IV} is closed 60 by stronger, and the circuit W^{III} by weaker illumination of the selenium cell. When the former circuit is closed the armature k of the electromagnet m of relay C is attracted, contact between q¹ and n is interrupted, and

catch l¹ lockingly contacts with the armature lever k². Upon the circuit W^{III} being closed, the armature l is attracted, the armature lever k² is electrically disconnected from the catch l¹, the armature beam k swings around and contacts with the contact spring n, and contact is made at q¹ for closing the circuit FS. 70

The operation of the arrangement according to Fig. 2 is the following:—Upon the selenium cell S^{II} being strongly illuminated, 75 more current will pass through the coils 1, the diaphragm is repulsed by the magnet 2 and the contactor beam 5 is pressed home on the contact 7, with the result that the relay C is operated to interrupt the switch 80 circuit at q¹, while on weaker illumination contact is made at 6 for closing the switch circuit FS at q¹.

The use of a diaphragm relay is of great importance, since such a relay responds 85 readily to very weak currents and current fluctuations. In the direct current system even rather violent contrasts are compensated for, the twilight switch device, though exceedingly sensitive, being highly insensitive 90 to shocks and jars, since the stiff iron diaphragm, which is under continuous magnetic stress, is not readily influenced by being jarred.

What I claim is:—

95 1. An electric twilight switch comprising in combination, an electric circuit, a light-sensitive cell in said circuit and controlling the current of said circuit, polarized electromagnets in said circuit and excited by said current, a diaphragm actuated by said electro-magnets, a contact device connected to and operated by said diaphragm and switch relay circuits controlled by said contact device for the hereinbefore specified purpose. 100

2. An electric twilight switch comprising in combination an electric circuit, a light-sensitive cell in said circuit and controlling the current of said circuit, polarized electromagnets in said circuit and excited by said current, a diaphragm actuated by said electro-magnets, a magnet secured to and vibrating with said diaphragm, a contact device operated by said diaphragm and switch relay circuits controlled by said contact device for the hereinbefore specified purpose. 105

3. An electric twilight switch comprising in combination, an electric circuit, a light-sensitive cell in said circuit and controlling the current of said circuit, polarized electromagnets in said circuit and excited by said current, a diaphragm actuated by said electro-magnets, a contact device in the form of a current rectifier connected to and operated by said diaphragm and switch relay circuits 110 controlled by said contact device for the hereinbefore specified purpose. 115

4. An electric twilight switch comprising

in combination an electric circuit, a light-sensitive cell in said circuit and controlling the current of said circuit, polarized electromagnets in said circuit and excited by said current, a diaphragm actuated by said electromagnets, a contact device connected to and operated by said diaphragm, and two switch relay circuits alternately closed by

said contact device, for the hereinbefore specified purpose.

In testimony whereof I affix my signature in presence of two witnesses.

EUGEN STEIGER.
